UNITED STATES PATENT OFFICE.

ALBERT N. CONNETT, OF LONDON, ENGLAND, ASSIGNOR TO GENERAL ELECTRIC COMPANY, A CORPORATION OF NEW YORK.

PLOW-RAISING MEANS FOR CONDUIT-RAILWAYS.

SPECIFICATION forming part of Letters Patent No. 729,137, dated May 26, 1903.

Application filed February 21, 1901. Serial No. 48,204. (No model.)

To all whom it may concern:

Be it known that I, ALBERT N. CONNETT, a citizen of the United States, residing at London, England, have invented certain new and useful Improvements in Plow-Raising Means for Conduit-Railways, of which the following is a specification.

This invention relates to railways of the type having working conductors beneath the car and collectors depending from the car for making connection between the working conductors and the car-motors.

The invention consists in means for controlling the movements and electrical connections of such collectors.

Of the drawings, Figure 1 is a cross-section of a portion of such railway, showing a truck of an electric car with which my invention is embodied. Fig. 2 is a plan view of the truck. Fig. 3 is a detail view showing means for varying the elevation of the collector and simultaneously changing its electrical connections. Figs. 4 and 5 are cross-sections of a road-bed, showing trucks provided with further features of my invention; and Fig. 6 is a plan of a roadway with a curved slot.

For the sake of simplicity no one figure contains all the features of the invention, although all features coöperate and many cars 30 are in successful operation which are provided with all the features disclosed.

The particular conductor system with which my invention is shown herein is the familiar underground-conduit system; but I regard 35 the invention as clearly applicable to any system which has working conductors beneath the car on or below the surface and which has a depending collector for engaging such conductors—as, for example, surface-stud-contact systems or third-rail systems.

It is frequently found desirable and necessary to employ at least two systems of working conductors on the same road, one system being at one portion of the road and the other 45 system at another portion of the road. In such a case one of the systems above described is generally used on one portion and an overhead system is used on another portion. However, any one system having conductors beneath the car might be used in the 50 same road with any other system having con-

ductors beneath the car or with an overhead-line system. The usual case is to have an underground-conduit system at one portion of the road—say within city limits—and at 55 the other portion to have an overhead-line system beyond the city limits. In any case since with at least one of the systems is employed a depending collector it is necessary that means be provided for raising that collector when the end of the system with which said collector operates is reached and to lower the collector when the first part of the section of the road provided with a system with which said collector operates is reached, and 60 in all such cases my invention, which consists of means for controlling movements and electrical connections, is applicable.

Since the slot in which the shank or reduced portions of the collector operates is necessarily small to prevent the engagement of vehicle-wheels therein and since it is necessary that the working parts of the collector within the conduit which engage with the conductors should be rather large, it is essential that 75 some means be provided to widen the slot between the upper portion of the protecting walls of the feeding-conductor to permit the withdrawal of the collector from the inclosure when desired—such, for instance, as that 80 shown in my application for patent, Serial No. 48,203, filed February 21, 1901.

Figs. 1 and 2 illustrate the means for raising and lowering the collector P after the conduit or inclosure has been opened. In normal operation the collector or plow is suspended from the car by a chain C at such an elevation that its contacts or shoes S can engage with the working-conductor rails R. Means are provided at the side of the car 90 whereby the chain can be controlled. The motorman having removed his controller-handle may use it to operate such means to raise or to lower the collector. Angle-irons G are suitably secured to the truck-frame, as shown, 95 to engage the fore and aft portions of the collector to prevent independent longitudinal movement of the collector with respect to the car. Guides G' are also mounted on the truck-frame, as shown, to engage the collector-shoes 100 S when the collector is raised and maintain the shoes in a central position to prevent them

from catching on the guides G. A wheel W is journaled in the frame, as shown, and from this wheel the chain and collector are suspended, the chain passing beneath a guide-wheel W², which is mounted in a stationary portion of the truck.

As shown more clearly in detail at the right in Fig. 3, a nut N is mounted on a worm-shaft M, and journaled on this nut is a wheel W', over which the chain C passes, as shown in Fig. 1, the end of the chain being secured to a stationary support C'. When the motor-man's controller-handle X is placed over the outer end of the worm-shaft M and the handle turned, the nut carrying the wheel W' will be moved along the shaft to the right from its position at the left in Fig. 1. The chain will thus be drawn under the wheel W² and over the wheel W and the collector be raised from the conduit which has been opened to permit its withdrawal. When the collector has nearly reached its raised position, the shoes S will engage the inclined guides G', which will maintain them and the shank of the collector in a central position. With this construction of worm-shaft and nut it will be seen that the chain is moved to a distance double the range of movement of the nut, whereby effective results are accomplished by a compact apparatus. A spring-operated latch A engages the nut in its movement toward the right and is forced by the spring into the return-path of the nut to prevent the return of the latter under the weight of the collector and securely locks the latter in its raised position. The latch is released by hand when it is desired to lower the collector.

In systems of this character it is essential that the electrical connections of the collector which has been withdrawn from its operative position should be broken and that the electrical connections of the collector which are substituted should be made at that time. This has hitherto been accomplished by hand; but I have devised an apparatus by which these changes are made automatically during the operation of raising or lowering the collector.

At the left in Fig. 3 the switch, with its electrical and mechanical connections, is illustrated. The motor O is permanently connected to the contacts O P and O N. A rotatable cylinder I carries four contacts, of which two, D D, are connected to the collector-shoes S. A third, D', is connected with the overhead trolley T or other suitable collector, and the fourth, D², is connected to ground. A crank-arm B is connected with the cylinder I, and a rod E is pivoted to this crank-arm. The right-hand portion of the rod E is screw-threaded, as shown, and double nuts F, shown at the center and the right-hand end, are screwed thereon to serve as stops. A sleeve V incloses the screw-threaded portion of the rod E, and along this sleeve slides the nut N, which is operated by the worm-shaft M. The rod E is continuously screw-threaded

in order to permit the nuts to be screwed on from the end, and the sleeve V provides a smooth surface for the sliding of the nut N. If the nuts were screwed upon the rod from opposite ends, the sleeve V would not be necessary. As shown in Fig. 3, the nut N is in its extreme right-hand position, the chain C having consequently been drawn up to raise the collector, and the nut has just engaged the right-hand stop F to force the rod E to the right and through the crank-arm B to partially rotate the cylinder I in the same direction. It will thus be clear that the switch I is not operated in either direction until the collector has nearly reached the end of its vertical travel. In this position of the cylinder I the connection of the motor-terminals O P and O N with the collector-shoes S have been broken and the motor-terminals have been connected with the contacts D' and D², which are connected with trolley and ground, respectively. When the worm-shaft M is turned in the opposite direction and the nut N moved thereby to the left, the connection of the motor with the trolley T will be maintained until the collector is about to assume its operative position—that is, the cylinder-switch will not be moved until the nut N has nearly reached the left-hand part of the worm-shaft M, when it engages the left-hand stop F to force the rod E to the right and turn the cylinder I to the left, breaking the trolley and ground contacts and making connection between the motor-terminals and the collector-shoes S.

Figs. 4, 5, and 6 represent means for controlling movements of the plows in addition to those movements already described.

In portions of a road the conduit will be located substantially midway between the track-rails, and the slot will be likewise located, being included between two independent slot-rails, as shown in the right-hand portion of Fig. 6. However, there are various conditions which make it desirable at other portions of the road that the conduit be located under one track-rail, the slot being included between such track-rail and a single independent rail. In such cases these central and side slots are made continuous by the curved slot-rails shown in the central portion of Fig. 6 in order that the curved slot-rails may guide the collector from one to another.

Owing to the distance between the slots shown at the left and right of Fig. 6, it is necessary that the collector should have a wide range of movement transversely of the car-body. The construction for accomplishing this result is shown in detail in Figs. 4 and 5. The upper portion of the collector P is provided with a head H, which engages in a slot L' in an elevator L, which is connected at the lower end of the chain C. As shown in Fig. 4, there are three of these elevators, one having a slot midway between the track-rails and one having a slot adjacent to each

track-rail, each elevator being provided with independent elevator mechanism. A guide-way G^2 connects these elevators, being in alinement with the slot L' in each elevator, so that the head H of the collector is free to move in the direction in which the curved slot-rails tend to move it to take its new position. The means for raising and lowering the central elevator is substantially as shown in Figs. 1, 2, and 3. The means for raising the side elevators consists of a chain C , secured to a wheel-segment W^3 , upon the axis of which an operating-chain is mounted. A wheel Q , provided with a pawl and ratchet, serves to operate this chain.

Inasmuch as the wide range of transverse movement of the collector requires unusually long leads D , means are provided for taking up their slack. Transverse guide-rods b are provided, and a carrier k is mounted for free movement upon these rods. To the carrier k are attached the leads from the collector, and when the collector is moved transversely to the car the carrier moves with it along the guide-rods b until it engages one of the fixed stops k' , to one of which the free ends of the leads are secured.

Having thus described my invention, what I claim as new, and desire to secure by Letters Patent, is—

1. The combination with an electric car, of a collector, chains attached to the forward and rear parts of said collector by which said collector is suspended, means around which said chains are adapted to pass and from which said chains are suspended, and means independent of said suspending means for drawing up and letting down said chains.

2. The combination with an electric car, of a collector, chains attached to the forward and rear parts of said collector, by which chains said collector is suspended, means around which said chains are adapted to pass and from which said chains are suspended, guides for the forward and rear parts of said collector, and means independent of said suspending means for simultaneously drawing up and letting down said chains.

3. The combination with an electric car, of a collector, a chain by which said collector is suspended having one end secured to a stationary part of the car, and means for forcing a portion of the chain out of its direct line of connection between said secured end and said collector to elevate the latter.

4. The combination with an electric car, of a collector, a chain by which the collector is suspended having one end secured to a stationary part of the car, a movable nut for forcing a portion of the chain out of its direct line of connection between said secured end and the collector, and a worm-shaft for actuating said nut.

5. The combination with an electric car, of a collector, a chain by which said collector is suspended having one end secured to a sta-

tionary part of the car, a movable nut for forcing a portion of the chain out of its direct line of connection between the secured end of the chain and the collector, a wheel for said chain journaled on the nut, and a worm-shaft for actuating said nut.

6. The combination with an electric car, of a collector, a chain from which said collector is suspended having one end secured to a stationary part of the car, a movable nut for forcing a portion of the chain out of its direct line of connection between the secured end of said chain and said collector, a wheel for the chain journaled in said nut, a guide-wheel journaled in a stationary support, and a worm-shaft for actuating said nut.

7. The combination with an electric car, of a collector, a chain by which said collector is suspended having one end secured to a stationary part of the car, a wheel around which said chain is adapted to pass and from which it is suspended, a guide-wheel, a movable nut for forcing a portion of the chain out of its direct line of connection between the collector and the secured end of the chain, and a worm-shaft for actuating said nut.

8. The combination with an electric car, of a collector, a chain by which said collector is suspended having one end secured to a stationary part of the car, a wheel around which said chain is adapted to pass and from which it is suspended, means for varying the length of the chain between the point of suspension and the point of connection with the collector by forcing part of said chain out of its direct line of connection, and means for automatically locking the collector at the desired elevation.

9. The combination with an electric car, of a collector, a chain by which the collector is suspended having one end secured to a stationary part of the car, a movable nut for forcing a portion of said chain out of its direct line of connection between the collector and the secured end, a worm-shaft for actuating said nut, and a latch adapted automatically to engage said nut to lock the collector in a raised position.

10. The combination with an electric car, of a collector adapted to coöperate with one conductor system, another collector adapted to coöperate with another conductor system, a switch comprising connections to both collectors and to the car-motors, means for varying the position of one collector with respect to its conductor system without operating said switch, and means whereby a further movement of said collector will operate said switch to disconnect such collector from, and connect the other collector with, the car-motors.

11. The combination with an electric car, of a collector adapted to coöperate with one conductor system, another collector adapted to coöperate with another conductor system, a rotatable switch for alternately connecting each with the car-motors, a crank for the

switch, and means for controlling the position of one of the collectors and simultaneously reciprocating said crank.

12. The combination with an electric car, of 5 a collector adapted to coöperate with one conductor system, another collector adapted to coöperate with another conductor system, a switch for alternately connecting each collector with the car-motors, a chain by which 10 one of said collectors is suspended secured to a stationary part of the car, a nut for forcing a portion of the chain out of its direct line of connection between the secured end of the chain and the collector, a worm for operating 15 said nut, and means whereby the nut actuates said switch.

13. In an electric railway provided with a conduit, the combination with an electric car, of a collector or plow extending into the conduit and engaging with the positive and negative working conductors therein, a second collector adapted to engage with a positive conductor, and a switch comprising positive and negative plow-contacts, collector and 25 ground contacts, and motor-contacts which coöperate alternately with the plow-contacts and with the collector and ground contacts.

14. The combination with an electric car, of a collector provided with collector-shoes, a 30 chain by which said collector is suspended, means for changing the elevation of said chain between its point of suspension and the collector; guides for the forward and rear portions of the plow, and guides which are engaged by the collector-shoes to maintain the collector in a central position.

15. The combination with an electric car, of a collector, a guide transversely arranged and fixed with respect to the car and along which 40 said collector travels, and means for raising and lowering said collector at two or more parts of said guide.

16. The combination with an electric car, of a collector, a fixed transverse guide, a head on 45 the collector adapted to slide along the guide, and means for raising and lowering said collector at two or more parts of said guide.

17. The combination with an electric car, of a collector, a transverse guide along which the 50 collector slides, and a plurality of elevators

at desired points along the guide with which the collector engages.

18. The combination with an electric car, of a collector, a transverse guide, elevators at desired points along the guide and adapted to 55 form continuations of the latter, and a head on the collector adapted to slide along said guide and engage with said elevators.

19. The combination with an electric car, of a collector, a transverse guide along which the 60 collector slides, elevators at desired parts of the guide, with which elevators the collector engages, chains by which said elevators are suspended, and vertical guides for the elevators.

20. The combination with an electric car, of a collector free to move transversely thereof, motor-leads extending from the collector, a support for the slack of the leads but forming no part of said leads, and transverse guides 70 along which the support is free to slide.

21. The combination with an electric car, of a collector suspended from said car, means for raising and lowering said collector, a transverse guide along which said collector slides, 75 flexible electrical conductors connecting said collector to the car-circuits, and means for supporting the slack of said flexible conductors intermediate their ends, said supporting means being free to move transversely of 80 said car.

22. In a conduit system of electric railway, the combination with an electric car, of a collector, a chain for suspending said collector from said car, a frame in which said collector 85 is capable of a rectilinear vertical movement, carried by said car, said frame also acting to prevent the longitudinal movement of said collector relative to said car, said collector being adapted to move transversely of said 90 car, and means comprising the walls adjacent to the slot in a conduit carrying the electrical conductors, for guiding said collector in its transverse movement.

In witness whereof I have hereunto set my 95 hand this 9th day of February, 1901.

ALBERT N. CONNETT.
